UNITED STATES PATENT OFFICE.

THOMAS S. HOMANS, OF BROOKLYN, NEW YORK, ASSIGNOR TO INTERTYPE CORPORATION, OF BROOKLYN, NEW YORK, A CORPORATION OF NEW YORK.

MATRIX RELEASING AND DELIVERING MEANS.

Application filed July 7, 1924. Serial No. 724,717.

To all whom it may concern:

Be it known that I, THOMAS S. HOMANS, a citizen of the United States, residing at Brooklyn, in the county of Kings and State of New York, have invented new and useful Improvements in Matrix Releasing and Delivering Means, of which the following is a specification.

The present invention relates to improvements in typographical machines and more especially to those of the general class shown and described in Letters Patent No. 436,532, granted September 16, 1890, to O. Mergenthaler, and it is more particularly applicable to machines of this general class which are constructed to hold two or more magazines, which contain respectively matrices belonging to different fonts or matrices having different type faces, and from which matrices may be drawn as desired and assembled to form composed lines of mixed matrices from which the type bars or slugs are cast, machines of this kind being known as of the mixed type.

The primary object of the present invention is to provide novel and improved means for controlling or effecting the release and delivery of the matrices from the different magazines preliminarily to their assembly in the line whereby the delivery of the matrices from the different magazines may be effected under the control of a single keyboard with the same speed and facility as is possible with machines of this class which are constructed to deliver matrices from a single magazine. Another object of the invention is to provide means which enables these purposes to be accomplished with the use of a minimum number of parts, and without increasing the width of the assembler front, thus enabling the use of the usual magazines of standard width.

To these and other ends the invention consists in certain improvements and combinations and arrangements of parts, all as will be hereinafter more fully described, the features of novelty being pointed out particularly in the claims at the end of the specification.

In the accompanying drawings:—

Figure 1 is a front elevation of a portion of a typographical machine embodying matrix releasing means constructed in accordance with the present invention;

Figure 2 represents a side elevation, partly

in section, of the right-hand side of the structure shown in Figure 1; and

Figure 3 is a perspective view, partly in section, and on an enlarged scale, illustrating in detail the elements which are operative to release or effect the delivery of matrices from the different magazines.

Similar parts are designated by the same reference characters in the different figures.

In the present instance, the invention is shown applied to a typographical machine of the linotype class, the various mechanisms of such machines being well known in the art and being generally similar to those shown and described in the Mergenthaler patent referred to above, and, hence, the invention is shown in connection with only the matrix releasing and delivery part of the machine to which the present invention is applied. The preferred embodiment of the invention is shown in the present instance and will be hereinafter described in detail, but it is to be understood that the invention is not restricted to the precise construction shown as equivalent constructions are contemplated and such will be included within the scope of the claims.

It will be understood that the present invention is applicable to machines embodying a plurality of matrix containing magazines from which the matrices may be drawn as desired and assembled at a common assembling point to form a composed line of mixed matrices, 1 designating the assembler belt generally used in machines of this class and which passes over pulleys 2 and 3, the belt being operative to receive matrices dropping through the assembler front 4 and to deliver the matrices for assembly in the assembly elevator which is located adjacent to the lower pulley 2. In the present instance, the invention is shown applied to a machine constructed to hold two magazines M and M'. These magazines may be of the same general kind as those shown and described in my prior U. S. Patent No. 1,153,078, granted September 7, 1915, and they may be provided at their lower ends with escapements m and m' of the same general kind as those illustrated and described in my said patent, these escapements serving to control the delivery of the matrices from the lower ends of their respective channels in the magazines. The magazines preferably are mounted in superposed relation and in in-

100
105
110

clined position, so that the matrices will feed by gravity from the upper rear ends adjacent to the distributor through the magazines to the lower forward ends thereof, from which points the matrices are delivered to the assembler front 4. Also, the forward ends of the magazines are preferably arranged in staggered relation substantially as is shown in my prior U. S. Patent No. 1,237,043, granted August 14, 1917.

The assembler front, designated generally 4, comprises a front plate 5, and a rear plate 6, these front and rear plates being spaced sufficiently to allow the matrices to descend edgewise between them, and partitions 7 which extend toward the assembler belt and provide passages between them through which the matrices pass on their way to the assembler belt.

The upper or matrix receiving part of the assembler front is branched to provide matrix passages or channels which lead from the lower or matrix delivery ends of the different magazines whereby matrices delivered from both magazines will be conducted to and received by the assembler front. Preferably, and as shown in the present instance, the lower branch of the assembler front which directs or conducts matrices from the lower magazine M' is formed by upper and lower plates 8 and 9 between which matrices may pass while standing edgewise, these plates 8 and 9 being attached or joined to the rear plate 6 of the assembler front and the matrix passageway between these plates communicating, through an opening formed in the rear wall 6, with the matrix passageway formed between the front and rear plates 5 and 6 of the assembler front, and partition means is provided for this branch whereby matrices passing therethrough will be introduced properly into the respective matrix passageways formed between the partitions 7. The partition means for this lower branch of the assembler front comprises preferably upper and lower partition members 10 and 11 which are alined with one another and also with the partitions 7 contained between the front and rear plates 5 and 6 of the assembler front, the partition members 10 and 11 being located between groups of the matrix channels in the magazine M' so that matrices delivered from the channels of this magazine will pass between the partition members 10 and 11, it being understood that the matrices M' while contained in the magazines are in edgewise position, as is shown in Figure 3 and occupy this position while passing between the plates 8 and 9 forming the respective branch of the assembler front, and it being also understood that a sufficient number of properly spaced partition members will be used to maintain the

matrices substantially in such edgewise position during their entry into the assembler front. The upper branch of the assembler front which receives the matrices from the upper magazine M may be formed by bending the rear plate 6 of the assembler front rearwardly, substantially as shown, so that its upper end will substantially aline with the lower matrix delivery end of the upper magazine, the upper ends of the partition plates 7 being correspondingly curved to conform with the curvature of the rear plate 6. The partition plates 7 may be secured to the rear plate 6 in any suitable manner, as, for example, by forming lugs 12 on the rear edge of each partition plate 7 and inserting these lugs through appropriately located slots 13 in the rear plate 6 and then passing a wire or rod 14 through apertures in the lugs; and the partition plates 10 and 11 may be similarly secured in place between the plates 8 and 9, the plates 10 and 11 being shown provided with apertured lugs 15 to extend through slots formed in the upper and lower plates 8 and 9 and wires or rods 16 extending through these lugs to retain these partition plates in proper position.

The escapements *m'* which control the delivery of matrices from the lower magazine M' are actuated by reeds 17 which are mounted in guides 18, 19 and 20, so that they may reciprocate vertically, a row of these reeds being provided, the number of which corresponds to the number of escapements employed for the lower magazine, and the upper ends of these reeds, which are preferably offset rearwardly from the lower portions thereof, as is shown in Figure 2, are arranged to act upon the respective escapements of the lower magazine, upward movement of any one of these reeds serving to actuate its respective escapement and thereby effect the delivery of a matrix from the corresponding channel of the magazine, as will be understood fully from my prior patent, No. 1,153,078.

The escapements *m* which control the delivery of matrices from the upper magazine M are actuated by a set of reeds 21, the lower portions of which are preferably arranged in a row opposite or parallel to the corresponding portions of the reeds 17 which actuate the escapements for the lower magazine. The upper portions of the reeds 21, however, pass through the branch of the assembler front through which the matrices from the lower magazine pass, and the present invention enables these reeds for the upper magazine escapements to be extended through this branch of the assembler front without interfering with the delivery of matrices from the lower magazine and without requiring an increase in the width of the assembler front. To accomplish this re-

sult, portions of the reeds 21 are so shaped and formed that they are substantially alined with and form, in effect, continuations of the partition members 10 and 11 so that the reeds are accommodated within the widths of these partition members, although the upper ends of these reeds are arranged in a row and in proper actuating relation with the escapements *m* which control the delivery of matrices from the upper magazine. The particular configuration of the intermediate portions of the reeds 21 is shown clearly in Figure 3. In the instance shown, a group of four reeds 21 are so shaped or formed that their intermediate portions are alined and extend through slots 22 in the plates 8 and 9, the slots 22 being in the same plane with the partition members 10 and 11 and the portions of the reeds 21 which extend through these slots occupying the same plane with and forming, in effect, continuations of the partition members 10 and 11. In this particular instance, one of the reeds 21 is bent forwardly in an edgewise direction as at *a*, thence bent laterally at *b* and then joined at *c* to the intermediate portion *d* of this reed which extends upwardly through the slots 22 in the plates 8 and 9, and above the plate 8 this reed is bent laterally as at *e*, then rearwardly, as at *f*, and then upwardly in an edgewise direction, as at *g*, its upper end terminating in a position to engage the actuating lug of its respective escapement *m*. The next adjacent reed 21 is bent edgewise and in a forward direction, as at *a'*, and thence laterally, as at *b'*, and it joins at *c'* its intermediate portion *d'*, this intermediate portion *d'* extending alongside the portion *d* of the adjacent reed and through the slots 22 of the plates 8 and 9, and this reed above the plate 8 being bent laterally, as at *e'*, thence rearwardly, as at *f'*, and thence upwardly at *g'* to bring its upper end alongside the upper end of the adjacent reed and in a position to engage the actuating lug of the respective escapement. Another reed 21 may have offsets *h* and *i* formed therein to aline its intermediate portion *j* with the slots 22 and with the intermediate portions of the other reeds 21 of the same group, and to bring its upper end into position to engage the actuating lug of its respective escapement. The fourth reed 21 of the group may have its portions below and above its intermediate portion *d''* offset to the opposite side of the respective slots 22, as shown in Figure 3, so that its lower end may be in a row with the lower ends of the remainder of these reeds and its upper end will be in a row with the upper ends of the remainder of the reeds 21 and in a position to engage the actuating lug of its respective escapement in the upper magazine. By forming the intermediate portions of the reeds 21 substantially in the manner described, they may pass through the channel through which the matrices pass from the lower magazine to the assembler front without interfering with the passage of such matrices, as the intermediate portions of these reeds are alined with and form, in effect, continuations of the partition members 10 and 11 so that the passing matrices will not catch upon these portions of the reeds, and moreover, these portions of the reeds will serve as partition means for properly directing the matrices from the lower magazine as they pass through the branch channel of the assembler front.

It will be understood that any desired matrix from either the lower or the upper magazine may be delivered for assembly into the line by actuating the corresponding reed 17 or 21. Means is provided whereby a reed of either set may be actuated with equal facility from a single keyboard. Preferably, and as shown in the present instance, a keyboard 23 is employed which may be substantially the same as that commonly used on machines of this class constructed to hold a single magazine. The keyboard mechanism 24 of such a keyboard actuates in well known manner vertically movable keyboard reeds 25 which are arranged in a row and correspond in number and arrangement to each of the rows of escapement actuating reeds 17 and 21, it being understood that the actuation of a key of the keyboard will set the keyboard mechanism corresponding to such key into operation, thus causing an upward movement of the respective keyboard reed 25. The keyboard reeds 25 are mounted to reciprocate in a frame 26, the lower portion of which is pivoted at 27 to the frame of the machine and the upper portion of the frame 26 is movable in a direction transversely of the rows of escapement actuating reeds 17 and 21 in order to bring the upper ends of the keyboard reeds 25 into working relation with either the lower ends of the reeds 17 or the lower ends of the reeds 21, according to the position occupied by the frame 26. Any suitable means may be provided for shifting the frame 26 to bring the keyboard reeds 25 into either of these two working positions, a lever 28 being shown in the present instance which is pivoted at 29 to a bracket 30 which may be fixed to any suitable part of the frame of the machine and the upper end of the lever 28 is operatively connected to the frame 26 by a link 31.

The mode of operation of the matrix releasing and delivery mechanism as herein described is briefly as follows: The delivery of the matrices from both magazines is effected by operation of the keyboard 23 in the manner usual in machines of this general class. When it is desired to assemble in the

line matrices belonging to the upper magazine, the lever 28 is set to bring the keyboard reeds 25 into their forward position, as shown in Figure 2, so that they will actuate the escapement-actuating reeds 21 which control the delivery of matrices from the upper magazine, and while the keyboard reeds 25 are set in this position, actuation of the keyboard will effect the delivery of 10 matrices from the upper magazine. Whenever it is desired to deliver to the line matrices from the lower magazine, the lever 28 is shifted to bring the keyboard reeds 25 into their rear position where their upper 15 ends register or aline with the escapement actuating reeds 17 which control the delivery of matrices from the lower magazine, and actuation of the keyboard will then cause matrices to be delivered from the 20 lower magazine. Obviously, the lever 28 may be easily and quickly shifted, during the composition of a line, to cause delivery of one or more matrices from either magazine to be effected at will, it being unnecessary to alter the position of the magazines 25 or to employ more than one keyboard.

The escapement-actuating reeds 21 are preferably made from flat stock, and if, for manufacturing or other reasons, it is found 30 desirable to increase the thickness of these reeds, or their intermediate alined portions, such may be done, in which case it is preferable to reduce the thickness of the upper partition members 10 and to taper them so 35 that their thicker portions are toward the reeds and their thinner portions are toward the matrix delivery end of the magazine, such construction enabling the matrices released from the magazine to be delivered 40 therefrom without obstruction and to pass the intermediate portions of the reeds without catching thereon.

It will be understood that each set of 45 reeds 17 and 21 is of a number corresponding to the number of matrix channels in the respective magazines, and that the number of reeds 25 corresponds to the number of characters represented on the keyboard 23. Each reed, after it has been elevated by the 50 keyboard mechanism 24 as the result of the actuation of the corresponding key of the keyboard, descends to its normal or lower position, in the manner the reeds usually operate in machines of this class. The descent of each of the reeds, after actuation, may be effected by gravity, or a spring may be provided, if desired, to insure the return 55 of each reed to its normal position.

The present invention enables matrices to 60 be released and delivered at will from one or another magazine during the assembling of matrices to compose mixed lines, with substantially the same speed and facility as may be accomplished in machines using a single magazine. The escapement-actuat-

ing reeds for the upper as well as the lower magazine are enabled to act directly upon the escapements of their respective magazines, yet no part of the matrix delivery throat or passageway leading from either 70 magazine is obstructed. By constructing and arranging the intermediate portions of the escapement-actuating reeds for the upper magazine so groups of these portions of such reeds occupy a common plane, in 75 edgewise relation, and in alinement with the adjacent portions of the assembler front partitions, it is rendered possible to extend these reeds directly through the branch or auxiliary matrix delivery channel of the 80 assembler front, and no change will be required in the matrix channels of the magazine in order to insure delivery of the matrices therefrom without lodging against these reeds, and, moreover, the reeds for the 85 upper magazine are accommodated in the spaces provided for the assembler front partitions, and, hence, the width of the assembler front is not increased; consequently, the machine is enabled to use the usual magazines of standard width. 90

I claim as my invention:—

1. In a typographical machine having a plurality of magazines provided with escapements for delivering matrices therefrom, partitions for guiding matrices delivered from the magazines, and escapement-actuating means having portions thereof operative in groups in the planes of said partitions. 95

2. In a typographical machine having a plurality of magazines provided with rows of escapements for delivering matrices therefrom, partitions for guiding matrices delivered for assembly from one of the magazines 105 and a plurality of escapement-actuating means having portions thereof grouped in planes transverse to the rows of escapements and operative in the respective planes of said partitions and having other portions thereof arranged in a row longitudinally of the respective row of escapements and in operative relation therewith. 110

3. In a typographical machine embodying a plurality of magazines having escapements for releasing matrices therefrom, partitions for directing matrices as they are released from the magazines for assembly, and groups of escapement actuating means, each group having portions thereof operative in the 115 plane of the respective partition and other portions thereof relatively offset for actuating respectively a plurality of magazine escapements. 120

4. In a typographical machine embodying 125 a plurality of magazines having escapements for effecting the delivery of matrices therefrom, partitions for guiding the matrices delivered from one of the magazines, and escapement-actuating devices for another of 130

said magazines having portions thereof lying in groups in the planes of said partitions.

5. In a typographical machine embodying a plurality of magazines having escapements for controlling the delivery of matrices therefrom, an assembler front having branches to receive the matrices delivered from the respective magazines and having partitions for guiding such matrices for assembly, and 10 escapement-actuating devices for said magazines, the escapement actuating devices for one of the magazines having portions extending in groups through one of the branches of the assembler front and occupying 15 the planes of the matrix-guiding partitions.

6. In a typographical machine embodying a pair of magazines arranged in superposed relation and having escapements for controlling the delivery of matrices therefrom for assembly, upper and lower channels for guiding the matrices delivered from the respective magazines, said channels having matrix-guiding partitions, and sets of reeds 25 for actuating the escapements of the respective magazines, portions of the reeds for the upper magazine being grouped and extending through the lower matrix guiding channel in substantially the planes of the matrix-guiding partitions therein.

7. In a typographical machine embodying a plurality of magazines having escapements for controlling the delivery of mat-

rices therefrom, matrix channels leading from said magazines and having matrix-guiding partitions therein, and reeds for actuating the magazine-escapements, the reeds for one of the magazines having portions thereof extending in groups through the matrix channel for another magazine, said grouped portions of the reeds being arranged in edgewise relation, and lying substantially within the planes of the respective matrix guiding partitions of said channel. 45

8. In a typographical machine embodying a plurality of magazines having escapements for controlling the delivery of matrices therefrom, channels for conducting therethrough matrices delivered from the respective magazines, said channels having matrix guiding partitions therein, and rows of reeds for actuating the escapements of the respective magazines, portions of the reeds of one row being grouped in edgewise relation in a direction transversely of such row and extending through one of the matrix conducting channels substantially in the plane of the matrix guiding partitions thereof and other portions of said reeds being relatively offset to cooperate with the respective escapements for the corresponding magazine. 55

In testimony whereof I have hereunto set my hand.

THOMAS S. HOMANS.
